UNITED STATES PATENT OFFICE.

EDWIN W. WEBB, OF CHICAGO, ILLINOIS, ASSIGNOR TO STANDARD CAR TRUCK COMPANY, OF CHICAGO, ILLINOIS, A CORPORATION OF NEW JERSEY.

CAR-TRUCK.

1,185,152.

Specification of Letters Patent. Patented May 30, 1916.

Application filed May 1, 1915. Serial No. 25,092.

To all whom it may concern:

Be it known that I, EDWIN W. WEBB, a citizen of the United States, residing at Chicago, in the county of Cook and State of Illinois, have invented certain new and useful Improvements in Car-Trucks; and I do hereby declare the following to be a full, clear, and exact description of the invention, such as will enable others skilled in the art 10 to which it appertains to make and use the same.

My invention relates to car trucks and has for its object to improve the same in the several particulars hereinafter noted.

15 Generally stated, the invention consists of the novel devices and combinations of devices hereinafter described and defined in the claims.

In the accompanying drawings which 20 illustrate the invention, like characters indicate like parts throughout the several views.

Referring to the drawings: Figure 1 is a view in side elevation showing a car truck 25 embodying my invention, the journal boxes being removed and the wheels being indicated in diagram; Fig. 2 is a transverse section taken through the truck on the line $x^2 x^2$ on Fig. 1, some parts being shown in 30 full; Fig. 3 is a horizontal section taken approximately on the irregular line $x^3 x^3$ on Fig. 1; and Fig. 4 is a detail in section on the line $x^4 x^4$ on Fig. 1.

The truck side frames 1 are cast steel or 35 malleable iron structures formed with top compression members, bottom tension members and bolster columns; all cast integral. These side frames 1 of the truck are formed with truck bolster openings, the lower portions of which are slightly narrower than 40 the upper portions. The side frames 1 are formed with central webs and with outwardly and inwardly projecting marginal flanges, and the tension members thereof, 45 at their central portions, are formed with spring receiving pockets 2 located, two on the outer side and two on the inner side of the central web. The inside pockets 2 are formed with projecting flanges 3 raised 50 above the bottoms of the pockets, and to which the truck cross ties 4 are riveted, or otherwise rigidly secured. The said cross ties 4, as shown, are rolled steel angle bars and the said flanges 3 are formed with both 55 horizontal and vertical portions to which

the horizontal and vertical flanges of the said angle bars are riveted, gusset plates 5 being preferably interposed between the said parts, as best shown in Fig. 2. The truck springs 6 are seated in pockets 2, and it is important to note that with the arrangement described, the lower ends of the said springs are brought down below the bottoms of the cross ties, thereby making possible the use of very high or long truck 65 springs, which are much in demand at the present time, without lowering the cross ties, and without increasing the height of the bolster and side frames. Also, this arrangement gives great and sufficient depth 70 to the central portions of the truck side frames to take care of heavy loads required in the present railway service.

The truck springs 6 support combined 75 spring caps and roller bases 7 provided with notches 8 in their ends, that embraces the bolster columns of the truck side frames and hold the said elements 7 for vertical movements and against horizontal movements. On their upper surfaces, the said combined 80 spring caps and roller bases 7 are concave, or self-centering roller seats 9, on which lateral motion rollers 10 are seated.

The truck bolster 11 is preferably of a 85 cast steel structure, and, at the under surface of its end portions, it is provided with roller seats 12 that rest upon the rollers 10. The truck bolster is thus mounted for limited endwise movements, transversely of the truck. To limit the endwise movements 90 of the said bolster, transversely of the truck, it is provided with integrally cast or formed stop lugs 13 that are arranged to engage the inner edges of the combined spring caps and roller bases 7. The endwise movements of the truck bolster are, therefore, 95 limited by the combined spring caps and roller bases, the latter being held against horizontal movements, transversely of the truck, or otherwise, by their engagement 100 with the bolster columns of the truck side frames.

In assembling the parts of a truck, the bolster is first pushed through the side frames. This can be done because there are 105 no stops on the sides of the bolster, and because the stops 13 do not engage with the bolster columns of the truck side frames. When the bolster is properly centered in 110 respect to the truck, it is raised up, and the

combined spring caps and roller bases are applied by inserting them into the openings while turned obliquely, in respect to a horizontal, and then turning them into horizontal positions while their notches 8 are aligned with the bolster columns. Here it may be noted that the column-engaging faces of the notches 8 are slightly rounded at 8^a (see Fig. 1), so that the above noted engagement is made feasible without excessive clearance. The combined spring caps and roller bases are then lifted up and the springs are then applied, and then the combined spring caps and roller bases are pressed down upon the springs and the rollers are applied.

By securing the cross ties to the inside of the frame, as described, they are kept high enough to permit all of the braking levers and co-operating parts to work free at a good height above the rails. I give sufficient riveting space for the cross ties, by the use of gusset plates 5 attached to the full width of the inside bracket or flange 3 and extending back to receive about three rivets lengthwise of the cross tie, one additional rivet being preferably placed in the vertical leg of the cross tie angle. The side frames are made amply strong by the wide base of the pockets and by the good height of the central web or rib.

What I claim is:

1. In a car truck, truck side frames having bolster openings and provided with spring seating pockets integral with their bottom tension members and provided with

inwardly projecting cross tie brackets raised above the bottoms of said pockets, gusset plates riveted to said brackets above the bottoms of said pockets, and a flanged cross tie having its ends riveted to said gusset plates and to said brackets and located entirely above the bottoms of said pockets.

2. In a car truck, truck side frames having bolster openings and provided with bottom tension members formed with central webs and with spring seating pockets located both in the inner and outer sides of said central web, and inside pockets having angular cross tie brackets raised above the bottoms thereof, and angle cross ties riveted to said brackets and located entirely above the bottoms of said pockets.

3. In a car truck, the combination with truck side frames having bolster openings and spring seats, of springs on said seats, spring caps on said springs guided for vertical movements by said side frames, but held thereby against lateral movements, lateral motion devices on said spring caps, and a truck bolster mounted on said lateral motion devices and provided with integral depending stop lugs engageable with said spring caps to limit the movements of said bolster transversely of the truck.

In testimony whereof I affix my signature in presence of two witnesses.

EDWIN W. WEBB.
